UNITED STATES PATENT OFFICE

PAUL G. PEIK, OF CHICAGO, ILLINOIS, ASSIGNOR OF ONE-FOURTH TO SAMUEL R. SWENSON, OF EVANSTON, ILLINOIS

LAMP

Application filed January 10, 1927. Serial No. 160,252.

My invention relates to improvements in lamps, and it consists in the combinations, constructions, and arrangements herein described and claimed.

5 An object of my invention is to provide a lamp of the acetylene type which is especially adapted to be used by miners, but which may be used efficiently as a railroad lamp.

A further object of my invention is to provide a device of the type described which can be used with safety in any mine, whether gaseous or not, and which will warn the user immediately when gas develops.

15 A further object of my invention is to provide a device of the type described which has a uniform generation of gas by providing a novel means for the uniform flow of water to the carbide.

20 A further object of my invention is to provide a device of the type described which encloses the flame, whereby the outside gases cannot be ignited.

25 A further object of my invention is to provide a device of the type described which has a free circulation of air for carrying off the heat of combustion.

30 A further object of my invention is to provide a device of the type described in which the burner may be ignited without opening the flame chamber.

35 A further object of my invention is to provide a device of the type described which has a novel means for protecting the main body of the lamp and the lens from the heat of the flame.

40 Other objects and advantages will appear in the following specification, and the novel features of the invention will be particularly pointed out in the appended claims.

45 My invention is illustrated in the accompanying drawings, forming part of this application, in which

Figure 1 is a front elevation of the device,

Figure 2 is a section along the line 2—2 of Figure 1,

Figure 3 is a section substantially along the line 3—3 of Figure 2, and

Figure 4 is a modified form of the water-feeding mechanism.

50 In carrying out my invention, I provide a

body portion composed of an outer casing 1 having a relatively large open end. The walls of the casing 1 taper inwardly from substantially adjacent the open end to an arcuate-shaped reflector 2. The casing 1 is provided with a relatively large opening 3 which is centrally disposed within the upper portion of the wall thereof. A relatively large cup-shaped member 4 having an outwardly extending integral flange 5 is disposed within the opening 3. A screen 6 which is formed of any suitable material, such as wire mesh, is disposed within the cup-shaped member 4 in engagement with the inner wall thereof. A relatively small cup-shaped member 7 having an annular flange 8 is disposed within the relatively large cup-shaped member 4 and the screen 6. The cup-shaped members 4 and 7 are provided with exhaust openings 9.

55 A conical-shaped member 10, which is of substantially the same shape as the casing 1, is disposed within the casing 1 and engages with the inner wall thereof. The conical-shaped member 10 is provided with an opening 11 which is in alignment with the opening 3. The conical-shaped member 10 is further provided with an inwardly extending annular flange 12, disposed concentric with the opening 11 and adapted to receive the flanges 5 and 8 of the cup-shaped members 4 and 7.

60 A cylindrical flue 13, having openings 14, one upon each side and at the rear thereof, and outwardly extending integral prongs 15, is centrally disposed within the cup-shaped member 7. The prongs 15 are receivable within recesses 16 in the flange 12 and are held against displacement by the flanges 5 and 8. The front portion 17 of the flue 13 serves as a baffle plate.

65 The casing 1 and the conical-shaped member 10 are provided with aligned openings 18 and 19, respectively, which are disposed upon each side of the center line of the casing at the lower portion thereof. The casing 1 at the openings 18 is bent outwardly for receiving screens 20.

70 A ring 21 having an inwardly extending flange 22 is provided with an outer lens 23 and an inner lens 24. Gaskets 25 are disposed upon each side of the lenses 23 and 24.

The ring 21 is receivable upon the open end of the casing 1 and may be locked in place by any suitable means, not shown. The lens 23 is composed of a non-shatterable material. The lens 24 is provided with a plurality of openings 26 at the lower portion thereof and a plurality of openings 27 at the upper portion thereof.

A water tank or receptacle 28 is provided with an inlet opening 29 in the upper portion thereof. The tank 28 is provided with threads 30 adjacent the lower portion thereof. An overflow tank 31 is rigidly mounted at 32 upon the rear of the reflector 2 and is provided with threads 33 which are adapted to receive the threads 30 of the tank 28. A tube 34 is centrally disposed within the overflow tank 31 and extends downwardly therethrough. A cylinder 35 is disposed concentric with the tube 34 and is rigidly secured at its lower extremity to the bottom 36 of the overflow tank 31, thus forming an auxiliary water tank 35'. The cylinder 35 is provided with circumferentially disposed openings 35''. The upper extremity of the cylinder 35 is closed when the water tank 28 is screwed in place. A wick 37 is disposed within the tube 34, completely filling the tube. The lower extremity 38 of the wick may extend beyond the tube for a short distance and the upper extremity 39 of the wick extends over the upper extremity of the tube and downwardly within the auxiliary tank.

A water check valve 40 extends through the water tank 28 and is adapted to engage with the valve seat 41 for governing the flow of water from the tank 28 into the auxiliary tank 35'. The valve 40 is provided with a hand wheel 42 at its outer extremity and threads 43 which engage with threads 44 of the tank 28. A shut-off valve 45 extends through the tank 28 and is adapted to engage with the wick 37 for stopping the flow of water through the wick. The shut-off valve 45 is also provided with a hand wheel 46 for adjusting the position of the shut-off valve.

A burner 47 is so positioned within the body portion that the flame from the burner will be in central alignment with the reflector 2. The burner 47 is centrally disposed between the intake openings 18 and 19 and extends rearwardly through the reflector 2 to a position adjacent the bottom of the overflow tank 31. A carbide receptacle 48 is removably secured to the overflow tank 31 by means of threads 49. The carbide is indicated at 50.

Special means is employed for igniting the gases passing from the burner. This means includes a high resistance coil 51 which is in electrical connection with contact points 52 of a plug 53.

From the foregoing description of the va-

rious parts of the device, the operation thereof may be readily understood. The water tank 28 is first filled with water and the water check valve 40 adjusted to the approximate position for permitting the desired amount of water to pass from the water tank. Before igniting the gas from the burner, the operator makes sure that the auxiliary tank 35' has the desired amount of water therein.

The wick 37 is so constructed that it will permit only a desired amount of water, i. e., the amount required by the burner to pass therethrough at a uniform rate and into the carbide container. As the water passes from the wick and drops upon the carbide, a gas is formed which passes through the burner 47. This gas may be ignited by placing the contact points 52 into a female socket, whereby a source of current will pass through the coil 51. The heat from the coil 51 is sufficient to ignite the gas passing from the burner.

A direct heat from the flame of the ignited gas strikes the flue 13 at the baffle plate portion 17. In this manner the heat from the flame is kept from contacting with the body portion and the lenses 23 and 24. The flue also draws the spent gas therethrough. The suction caused by drawing the spent gas through the flue 13 causes air to be drawn in through the intake openings 18 and 19 around the burner and around the flue, where the air mixes with the spent gas before they pass outwardly through the screen 6. The upper ends of the flue and the cup-shaped members 4 and 7 are closed. The upper end of the flue 13 is spaced away from the upper ends of the cup-shaped members 4 and 7, permitting an air space therebetween for keeping the closed ends of the cup-shaped members 4 and 7 relatively cool. This is to avoid the igniting of gas within the mine. A portion of the air entering the intake ports 18 and 19 passes through the openings 26 between the lenses 23 and 24. In this manner the non-shatterable lens is protected from the direct heat of the flame and is thus kept cool.

The uniform passage of water down the wick is dependent upon maintaining a uniform level of the water in the auxiliary tank. Thus the cylinder 35 is disposed relatively close to the wick 37, whereby the desired amount of water will be supplied to the wick, irrespective of the position at which the lamp is held. The flow of water through any mechanical valve, such as 41, is increased through any shaking of the lamp which occurs when in use. This increased flow passes off through the openings 35'', thus maintaining the uniform level of water desired and necessary for the uniform passage of water down the wick. The overflow tank 31 is sufficient to receive all the excess water which might pass through 41.

Should the operator wish to shut off en-

tirely the supply of water to the wick, the shut-off valve 45 may be moved downwardly, thus holding the upper portion of the wick in close engagement with the upper extremity of the tube 34. Any of the parts which may be damaged by the flame during long use, such as the flue 13, the cup-shaped members 4 and 7, or the screen 6, may be removed from the body portion by first removing the lenses 23 and 24 and the conical-shaped member 10.

In Figure 4 I have shown a modified form of the water-feeding mechanism which is composed of a water tank 60 having a tube 61 extending through the bottom thereof and a carbide container 62, which is removably secured to the water tank 60. A wick 63 extends through the tube 61 and over the upper edge thereof. A water check valve 64 is movably disposed within the upper wall of the water tank 60 and is adapted to be moved into engagement with the wick 63 for varying the amount of water passing through the wick and cutting off the entire passage of water through the wick if desired. A burner 65 is disposed in communication with the carbide container 62.

I claim:

1. In a device of the type described, a body portion having an air intake port and an air exhaust port, a non-shatterable outer lens, an inner lens, means for securing said lenses to said body portion, said inner lens having openings therethrough, whereby the air from said intake port may pass through the openings in said inner lens between said lenses and out through said exhaust port.

2. A device of the type described comprising a body portion, a burner for the ignition of gas disposed in said body portion, means for supplying a predetermined quantity of gas to said burner, a flue extending through said body portion and provided with a transversely extending wall arranged to direct the heat of the ignited gases away from said body portion, said flue having a closed end and openings positioned substantially adjacent said closed end, a cover for said flue disposed over said closed end and positioned away therefrom, forming an air space therebetween, said cover composed of cup-shaped members disposed one within another and having their side walls spaced apart and provided with aligned openings, and porous means disposed between the side walls of said cup-shaped members and the openings therein.

3. A device of the type described comprising a body portion composed of a casing having an opening therein, a bell-shaped member arranged to be disposed in said casing and having an opening therein in alignment with the opening in said casing, an annular flange disposed concentric with the opening in said bell-shaped member, a flue

having projections arranged to be disposed upon said flange, and cover disposed over said flue and having an outwardly extending flange arranged to be disposed between said annular flange and said casing adjacent the opening therein.

4. A device of the type described comprising an outer casing having an opening therein, an outer cup-shaped member having openings therein, an inner cup-shaped member having openings therein disposed in registration with the openings in said outer cup-shaped member, porous means disposed between said outer cup-shaped member and said inner cup-shaped member, and means for securing said cup-shaped members to said outer casing.

5. A device of the type described comprising an outer casing having an opening therein, an outer cup-shaped member having openings therein, an inner cup-shaped member having openings therein disposed in registration with the openings in said outer cup-shaped member, porous means disposed between said outer cup-shaped member and said inner cup-shaped member, means for securing said cup-shaped members to said outer casing, said securing means comprising outwardly extending flanges integral with said cup-shaped members, and an inner casing having an opening therein and a recess disposed adjacent said opening for receiving said flanges and for securing said cup-shaped members to said outer casing when said inner casing is disposed within said outer casing.

6. A device of the type described comprising an outer casing having an opening therein, an outer cup-shaped member having openings therein, an inner cup-shaped member having openings therein disposed in registration with the openings in said outer cup-shaped member, porous means disposed between said outer cup-shaped member and said inner cup-shaped member, means for securing said cup-shaped members to said outer casing, said securing means comprising outwardly extending flanges integral with said cup-shaped members, an inner casing having an opening therein and a recess disposed adjacent said opening for receiving said flanges and for securing said cup-shaped members to said outer casing when said inner casing is disposed within said outer casing, a flue extending into and spaced away from said cup-shaped members, and means for securing said flue in place.

PAUL G. PEIK.
